VINCENTÉ SZAMIER, OF TERRYVILLE, CONNECTICUT.

SAFETY-LAMP.

1,104,941.

Specification of Letters Patent. Patented July 28, 1914.

Application filed January 9, 1913. Serial No. 740,902.

To all whom it may concern:

Be it known that I, VINCENTÉ SZAMIER, a citizen of the United States, and a resident of Terryville, in the county of Litchfield 5 and State of Connecticut, have invented certain new and useful Improvements in Safety-Lamps, which improvements are fully set forth in the following specification.

This invention relates to improvements 10 in fluid-burning lamps, and more particularly to fluid-burning lamps of the so-called safety type. Its object is to provide a lamp of the character above indicated which shall be simple and inexpensive as regards construction; durable, efficient and reliable in 15 practical service; which shall embody features of construction whereby is automatically effected, under adverse conditions of the lamp, the practical isolation of the wick 20 thereof from the main body of the fluid contained within its reservoir; and which shall possess certain well-defined advantages over prior analogous constructions.

The invention consists in the combinations, 25 details and parts whereby, together with the novel disposition and relative arrangement of said parts, the attainment of the foregoing object is rendered practicable, all of 30 which will be hereinafter more specifically referred to and set forth in the appended claims.

The invention is clearly illustrated in 35 the accompanying drawings, wherein similar reference-numerals denote like parts throughout the respective views, of which:

Figure 1 is a view showing, in elevation, 40 a safety lamp embodying my said improvements, a portion of the wall of the reservoir, with its jacketed neck, and of the interior 45 wick-casing, being broken away. Fig. 2 is a bottom plan view of the valved, interior wick-casing, detached, the scale being enlarged. Fig. 3 is an enlarged, detail sectional view of the lower, valved portion of 50 the wick-casing, the section being taken centrally and vertically thereof, as along the line α — α of Fig. 2.

In carrying out my invention, reference 55 being had to the accompanying drawing, I make use of a reservoir or font 2, which may be constructed of glass, metal, or any other suitable material, said reservoir being provided at its top with the usual neck 2', and supported by any appropriate standard or base 2''.

3 denotes the customary jacket, taking

over and inclosing, in the usual manner, the neck 2', said jacket being interiorly threaded to permit the attachment thereto of the burner 3'.

There is let endwise into the reservoir 2, by way of its neck aforesigned, a wick-casing 3'', here shown as being tubular in cross-section, and secured at its upper portion to the interior wall of the neck 2' by 60 means of cement 4, although any other suitable fastening element or elements may be availed of to this end. The wick-casing 3'' is open only at its top, to receive the wick 4', which depends interiorly therealong 65 from the burner 3', and at or near its bottom, to establish communication between its interior and the interior of the reservoir 2, the wall of said casing being intact, accordingly, from its top to a point at or near 70 its bottom.

Where a lamp or the like is fitted with the foregoing safety device or attachment, the level of the fluid contents of its wick-casing 3'' will register with the level of the 80 fluid contents of its general reservoir 2, thereby, when such lamp occupies an upright position, practically sealing, at all times, the casing 3'' against the inrush of air by way of its open top, substantially 85 isolating the wick 4' from the contents of the general reservoir aforesigned, and accordingly preventing the explosion of such lamp. The foregoing applies also when the lamp shall have been upset, accidentally or 90 otherwise, providing, under such adverse conditions, the contents of the reservoir of the lamp is sufficient to cover the wick-casing 3'', or the contents of said wick-casing shall chance to be sufficient to seal the same 95 against the inrush of air interiorly therealong. Accordingly, to insure the effectual sealing of the casing 3'', particularly when the lamp shall have been tipped to a position beyond the horizontal, and irrespective 100 of the volume of the fluid contents of the reservoir 2, or the casing 3'', I provide the latter, at or near its bottom, with an annular valve-seat 4'', the same, by preference, being situated within said casing, and 105 formed integral therewith by annularly insetting the wall thereof, as at the point 5, and as clearly illustrated in the drawing.

5' denotes an independently-operable gravity valve, cut under marginally at an 110 inclination downwardly from its circumferential edge to a point along its bottom

suitably removed from its axis, to provide space, accordingly, for the occupancy or passage, between said valve and that portion of the reservoir 2 immediately thereunder, 5 of more or less of the fluid contents of said reservoir, said valve, also in this connection, and to further subserve the purpose above stated, being, by preference, dished or concaved centrally at its under surface, as indicated by 5'', Figs. 2 and 3. When the lamp occupies its upright position, valve 5' stands, by its own gravity, slightly though sufficiently removed downwardly from its seat 4'' to provide more or less of an annular passage, 6, by way of which communication is established between the interior of the reservoir 2 and the interior of the casing 3'', more or less of the contents of the former passing into the interior of the latter, or outwardly therefrom, accordingly; and for holding the valve 5' thus slightly removed from its seat 4'', although in this connection I purpose cutting away at suitable intervals the lower circumferential margin of the casing 3'', to form, integral with said casing and at suitable intervals circumferentially along its lower edge, valve-retaining tabs 6', which are collectively turned inwardly toward the axis of said valve, and which take 20 under the same, respectively, at the under, inclined margin thereof, all as clearly illustrated in the drawing.

The total area of the passage 6, when open, is materially less than the total area 35 aforesigned provided by inclining the under margin of the valve 5', as stated; and pronouncedly so where said valve is dished or concaved centrally at its under face, also as above stated. Hence, during any tilting 40 action of a lamp fitted with my improved safety attachment, the pressure of such volume of the fluid contents of the reservoir 2, as may seek to pass between the valve 5' and that portion of the bottom of said reservoir 45 immediately thereunder, will be materially greater than the pressure against the opposite or active face of said valve by such lesser volume of the contents of said reservoir, as may seek to enter the casing 50 3'', by way of the passage 6, the closure, automatically, of the valve 5' against its seat 4'', being, accordingly, strongly induced, although said lamp may not have been tilted fully into a horizontal position. 55 Again, upon said lamp being tilted or upset in a manner to assume a position more or less beyond the horizontal, valve 5', even if unaided by any volume of the contents of the reservoir 2, as above defined, will automatically, by its own gravity, seek and engage its seat 4'', thus effectively preventing the entrance of air into the reservoir 2, by way of the casing 3'', as from the top thereof, and this irrespective of whether or not 65 the contents of the reservoir 2 be of such

volume as to cover the casing 3'', or the latter contain such volume of fluid contents as would effectually seal the interior thereof, all when said lamp occupies its said upset position. Accordingly, under the foregoing 70 conditions, the wick 4' being wholly isolated from the contents of the general reservoir 2, the entrance of air into said reservoir, by way of said casing, being wholly precluded, explosion of the lamp, when fitted with my improved safety device or attachment, becomes wholly obviated. 75

The casing 3'' is formed from any suitable material, preferably metal in thin sheet-form, and the valve 5' is also formed from 80 any suitable material, as metal, porcelain, or the like.

In the absence of an adequate vent for the reservoir 2, the same may be filled by way of the usual exterior nozzle, as 6'', and the latter may be closed by the usual cap, as 6'''.

It will be seen that my improved safety lamp is well adapted for the purposes for which it is intended, and further that the same may be modified to some extent, particularly as regards the manner in which valve-seat 4'' is provided, the general form of the valve 5', and minor details of the general construction, without departing from the scope of the appended claims.

I claim:

1. The combination with a reservoir and an oil-burner, of a wick-casing and an independently-operable valve, said wick-casing having tabs formed thereon and provided with an interior valve-seat, said valve being held, through the medium of said tabs, in coöperative relation to said valve-seat, with substantially the whole of its lower face exposed to the direct action thereon of the fluid contents of said reservoir, and communication being established laterally between said wick-casing and said reservoir and automatically controlled by the valve aforesigned upon the reservoir being tipped. 100

2. The combination with a reservoir and an oil-burner, of a wick-casing and an independently-operable valve, said wick-casing having tabs formed thereon and provided with an interior valve-seat formed 105 integral therewith, said valve being held, through the medium of said tabs, in coöperative relation to said valve-seat, and communication between said wick-casing and said reservoir being duly established and 110 automatically controlled by the valve aforesigned upon the reservoir being tipped. 115

3. The combination with a reservoir and an oil-burner, of a wick-casing and an independently-operable valve, said wick-casing having tabs formed thereon and provided with an interior valve-seat formed by 125 annularly insetting the wall thereof, said valve being held, through the medium of said tabs, in coöperative relation to said 130

valve-seat, and communication between said wick-casing and said reservoir being duly established and automatically controlled by the valve aforesigned upon the reservoir being tipped.

4. The combination with a reservoir and an oil-burner, of a wick-casing and an independently-operable valve, said wick-casing having tabs formed thereon and provided with an interior valve-seat, said valve being held, through the medium of said tabs, in coöperative relation to said valve-seat and having its lower face recessed and exposed to the direct action thereon of the fluid contained in the reservoir, communication between the latter and said wick-casing being duly established and automatically controlled by the valve aforesigned upon the reservoir being tipped.

5. The combination with a reservoir and

an oil-burner, of a wick-casing and an independently-operable valve, said wick-casing having tabs formed thereon and provided with an interior valve-seat formed by annularly insetting the wall thereof, said valve being held, through the medium of said tabs, in coöperative relation to said valve-seat and having its lower face recessed and exposed to the direct action thereon of the fluid contents of the reservoir aforesigned, and communication being established laterally between said wick-casing and said reservoir and automatically controlled, upon the latter being tipped, by the valve aforesigned.

VINCENTÉ SZAMIER.
